SHUTTLELESS LOOM

Carl F. Libby, Stoughton, Mass.

Application February 26, 1937, Serial No. 127,884

10 Claims. (Cl. 139—124)

This invention relates to looms. It is an object of the invention to provide an improved loom which is capable of considerably higher speeds of operation than looms heretofore in use. For this purpose, according to the invention, reciprocating parts are eliminated as far as possible, the movement of the various parts being in paths which follow closed curves. Moreover, to avoid delays due to stopping to replenish shuttles, the invention is shown and described as embodied in a shuttleless loom wherein the filling is drawn directly from one or more thread bodies. The weft or filling is inserted into the shed by a pair of fingers entering the shed alternately from opposite sides and leaving within the shed loops of filling yarn. Novel reed structure is also provided to beat up the filling toward the fell of the fabric. In order to retain the loops of filling within the shed and to form proper selvages on the fabric, a knitting needle is provided on each side of the shed to receive the loops of filling deposited therein from alternate sides by the respective fingers. These needles knit each loop through the preceding loop, thus forming knitted selvages. While the invention is not to be limited to looms of any particular width, the embodiment hereinafter described is more particularly suitable for the weaving of relatively narrow webs.

Various advantageous features of structure will be apparent to one skilled in the art from a disclosure of the invention in the description thereof which follows and in the drawings of which.

Figure 1 is a side elevation of a loom embodying the invention.

Figure 2 is a plan view showing a diagrammatic arrangement of the warp threads, the filling yarns, the yarn fingers and the knitting needles employed in the loom.

Figure 3 is a partial plan view of the loom shown in Figure 1.

Figure 4 is a fragmentary perspective view of the end portions of a yarn finger and a knitting needle.

Figure 5 is a fragmentary plan view of a portion of the apparatus shown in Figure 3, but on a larger scale.

Figure 6 is a section on the line 6—6 of Figure 3.

Figure 7 is a section similar to Figure 6 but showing the movable parts in a different position of operation.

An example of the type of fabric which can be woven on the loom illustrated on the drawings is shown in Figure 2 wherein the warp threads

are indicated at A. Two filling yarns B and C are employed, these yarns being deposited in the shed alternately in loops from opposite sides and knitted into the preceding loop of the same yarn. Thus in Figure 2 the loop D in the filling yarn B has been knitted through the preceding loop E in the same yarn. The loop F in the yarn C, which has just been deposited in the shed, is about to be knitted through the preceding loop G in the same yarn. Thus each of the selvages 10 is formed by knitting successive loops of one of the filling yarns.

Figures 1 and 3 illustrate a loom for weaving narrow fabrics or webs, such as that shown in Figure 2. The loom is provided with a main frame 20, a number of heddles 22, a breast beam 24, a fabric take-up roll 26, and an idle roll 28 journaled in a rockable frame 29 and resting on the roll 26. The roll 26 is immediately below the presser roll 28 and is hidden by the roll 28 in Figure 3. The warp threads are led from a suitable warp supply (not shown) at the rear of the loom through the eyes of the heddles 22 so as to form a shed between the heddles and the breast beam 24, as indicated in Figures 6 and 7, in a manner well known in the art.

For the weft two filling yarns are supplied respectively to a pair of fingers 30 and 32 from conveniently located thread bodies (not shown). The finger 30 fits slidably in a guide element 34 which is rockable about a vertical axis. An end of the finger is connected as at 36 to a crank 38 in the manner of a pitman. The crank revolves about the axis of a vertical shaft 40 on which it is mounted. As shown in Figure 3, the shaft 40 rotates in a counter-clockwise direction. The free end of the finger 30 is provided with an eye 42 for one of the filling yarns. In like manner, the finger 32, similar to the finger 30, fits slidably in a rocking guide 44, one end of the finger being 30 pivotally attached as at 46 to a crank 48 which revolves about the axis of a vertical shaft 50 on which it is mounted. The shaft 50 rotates in a clockwise direction.

Cooperating with the fingers 30 and 32 are a pair of knitting needles 52 and 54 (Figure 2). These needles are carried respectively in carriage blocks 56 and 58 which are disposed along opposite side edges of the breast beam 24. The knitting needles are longitudinally slidable in their respective carriage blocks, the blocks themselves being rockable so as to tilt upwardly, as indicated in Figures 1 and 6, to avoid interference with the fingers 30 and 32.

A reed is provided for beating up the filling 55

toward the fell of the web. As shown, the reed comprises a series of stationary dents 60 and a double series of movable dents 62a and 62b, the latter being portions of elongated plates 62 which are mounted in parallel spaced relation on a shaft 66. The stationary dents 60 are spaced parallel plates arcuate in shape, each dent presenting a concave arcuate edge 68 which is concentric with the shaft 66 on which the plates 62 are mounted. 5 As shown in Figures 6 and 7, the dents 62a and 62b are symmetrical with respect to the shaft 66, the plates 62 being keyed to the shaft 66 as by a suitable key 70 and spaced from each other by suitable washers 72. The stationary dents 60 10 are likewise spaced by washers of the same thickness so that the dent plates 62 are accurately aligned with corresponding dents 60. Each dent 62a and 62b presents a convexly curved edge portion 74 near the end thereof, this edge portion being eccentric with respect to the shaft 66 so as to engage the filling of the shed and to beat it up toward the fell of the web as the movable dents revolve with the shaft 66. Each of the dents 62a and 62b is preferably concaved as 15 20 25 at 76 along its rear edge so as to avoid interference with the yarn fingers 30 and 32. The stationary dents 60 are mounted with respect to the shaft 66 in such a manner that the extreme tips of the movable dents 62a and 62b pass very close to the concave edges 68 of the stationary dents 60, there being a clearance of only a few thousandths of an inch. The warp threads from the heddle eyes pass through the spaces between successive dents 60. Since the dent plates 62 30 35 40 are adjusted so as to be in the same planes with corresponding fixed dents 60, and the ends of the moving dents almost touch the edge 68 of the fixed dents, there is no possibility of the dents 62a and 62b passing between the wrong warp threads as they enter the shed.

The filling yarn is laid in the shed in loops by the action of the fingers 30 and 32. The action of the finger 30 is illustrated in Figure 5, the finger entering through the wide portion of the 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

pivot 86 near its rear end. At a point 88 near its front end, the carrier 56 is pivotally attached to a link 90 which extends down and is pivoted as at 92 to a pitman 94. This pitman is connected at 96 to a crank wheel 97 which is mounted on a shaft 98. The pitman 94 is slotted as at 100 so as to be guided by a fixed pin 102 which rides in the slot. Rotation of the shaft 98 causes the pitman 94 to reciprocate relatively to the pin 102 and also to rock about that pin as a 10 pivot, thus imparting a peculiar rocking movement to the needle carriage 56. Longitudinal sliding movement is imparted to the needle itself by a rocking lever 104 which is notched as at 106 to receive a needle tab 108 at the base of the 15 needle 52. The lever 104 is connected as by a link 110 to the pitman 94 as indicated in Figures 6 and 7. Thus rotation of the shaft 98 results in a reciprocation of the knitting needle 52, this reciprocatory motion being combined with a tilting movement as the needle carriage 56 is rocked by rotation of the shaft 98. Similar mechanism is provided for the actuation of the knitting needle 54 and its carriage 58 through a similar shaft 98. 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

In order to draw each of the filling yarns from their respective yarn bodies for the fingers 30 and 32 at an approximately constant rate, a movable yarn guide is supplied for each of the fingers. As shown in Figures 1 and 3, a yarn guide 112 is provided for the finger 30, the yarn being led from a yarn body (not shown but preferably mounted at the rear of the loom) through the eye 112, then through an eye 113 carried adjacent to the pivoted end of the finger, and then 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

The various mechanisms hereinbefore described may be driven from a main drive shaft 150 on which is mounted a pulley 152 carrying a 65 belt 154 through which the pulley wheel is rotated by any suitable source of power. On the shaft 150 is mounted a pinion 158 which meshes with a pinion 160 mounted on the shaft 66. As previously mentioned, the movable dents of the reed are also mounted on the shaft 66. This shaft extends across the entire machine. At its ends are mounted a pair of pinions 162. Each pinion 162, as indicated in Figure 3, meshes with an idle pinion 166 which in turn meshes with a pinion 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

168 mounted on one of the shafts 98 for the operation of the corresponding knitting needle and its carriage as hereinbefore described. Since the driving connections between the shaft 66 and each of the shafts 98 are similar, the same reference characters have been used for corresponding parts.

For driving the yarn fingers 30 and 32, a pinion 170 is mounted on the main drive shaft 150 so as to mesh with a gear wheel 172. The latter meshes with a pinion 174 mounted on the shaft 122. This shaft carries a pair of bevel gears 176 which mesh respectively with corresponding bevel gears 178, the latter being mounted respectively on the vertical shafts 40 and 50 which drive the yarn fingers as hereinbefore described.

For operating the heddles 22, the gear wheel 172 is mounted on a horizontal shaft 180 on which is also mounted a bevel gear 182 meshing with a corresponding gear 184 which in turn is mounted on a shaft 186. On the shaft 186 are mounted suitable cams 190 which act through cam followers 192 to reciprocate the heddles 22 in a manner well known in the art.

For driving the take-up roll 26, the shaft 186 carries a worm 192 which meshes with a worm gear 194 mounted on a shaft 196. This shaft is connected through a suitable train of gears, inclusively indicated at 200, to a shaft 202 on which is mounted the fabric take-up roll 26. By changing some of the gear wheels in this gear train for gear wheels of different sizes, the rate of rotation of the take-up roll 26 can be regulated.

The operation of inserting a loop of filling and beating up the loop in the fabric takes place in the following manner. Referring to Figure 5, successive portions of the guide eye 42 in the end of the finger 30 are indicated by #1, #2, #3, #4, #5, #6, #7 and #8. The position corresponding to #1 is the same as that illustrated in Figures 1 3 and 6. The successive positions indicated by these numbers are spaced by equal intervals of time, each interval corresponding to $\frac{1}{6}$ of a revolution of the crank 38. Thus it is apparent that, when the finger 30 is in the position indicated by #1, it is swinging very rapidly through the shed to the position illustrated in Figure 4 wherein it catches the loop of filling on the hook of the needle 54. This movement of the finger 30 closely follows the movement of the reed dents 62a as they beat up the filling loop which has just been inserted by the other finger 32. When the finger 30 reaches the position illustrated in full lines in Figure 5, that is, between positions #1 and #2, the knitting needle 54 is projected rearwardly to be in position to receive the loop of filling from the finger 30. At the same time, the needle 52, which has received the previous loop from the finger 32, has been fully retracted to cast off the old loop and is now being advanced to move the new loop below the latch. As it moves, it is tilted up, as previously described, so as to ride over the finger 30 and to avoid interference therewith. The finger 30 is then rapidly retracted from the shed, leaving the loop of filling hooked over the needle 54 and in the front portion of the shed close to the fell of the web. The instant the end of the finger clears the shed, the heddles are actuated to change the shed and the dents 62b swing through the shed to beat up the filling. During this movement of the finger, the guide eye 112 has been swinging toward the front of the loom so as to draw yarn from the yarn body for quick supply to the finger when it is projected toward the right through the guide

34. The movement of the eye 42 from position #4 to position #5 is relatively slow, amounting practically to a brief pause during which the newly inserted loop of filling is beaten up and locked in position by the changing of the shed. As the eye of the finger 30 moves from position #5 to position #8, the guide eye 112 swings toward the rear of the loom so as to supply yarn quickly to the finger without jerking it from the thread body. Since the end of the finger enters the rear of the shed, the operation of the heddles can be completed as the finger is entering the shed. This affords an ample period of time for the shifting of the heddles, which is important when operating the loom at high speed. The movements of the finger 32 from the opposite side of the warp are symmetrical with those hereinbefore described for the finger 30. Since the various positions indicated by numbers in Figure 5 represent equal intervals of time, it is evident that, then the finger 30 is in any one of the positions indicated, the finger 32 will be in a corresponding position four stations from the finger 30. For example, when the finger 30 is at position #3, the finger 32 will at the same instant be in a position corresponding to that indicated by #7.

The movements of the fingers, needles and reeds are properly correlated to avoid interference and to minimize idle periods in the cycles of operation of these parts. Thus, as is evident from a comparison of Figures 5, 6 and 7, the filling fingers and sets of reed dents alternately enter the shed at the rear, move forward therein, and move out at the forward end, each finger entering the shed before the preceding set of reed dents has moved out of the shed at the fell, and each set of reed dents entering the shed before the preceding finger has been retracted from the shed. Thus at all times there is at least one forwardly moving member within the shed. The reed shaft 66, the cranks 38 and 48, the knitting needle drive shafts 98, and the cranks 136 for the yarn guides all revolve at the same speed. During a single revolution of each of these parts, two loops of filling are inserted in the shed and beaten up. This, in conjunction with other factors such as the curved paths followed by the free ends of the filling fingers, results in a loom which is capable of operation at phenomenally high speeds.

It is evident that many modifications and changes may be made in the loom herein shown and described without departing from the spirit or scope of the invention as defined in the following claims.

I claim:

1. In a loom, shed-forming means, a filling finger on each side of said shed, each said finger having a guide eye for filling yarn in the free end thereof, and means for swinging each said finger about a pivot so that said end enters the wide end of the shed, is projected through to the opposite side of the shed, is retracted along a path adjacent to the fell of the fabric, and is advanced along the side of the shed to a point adjacent to the wide end thereof, said advancing movement of each finger along the side of the shed taking place during the movement of the end of the other finger into and out of the shed.

2. In a loom, shed-forming means, a finger for projecting loops of filling yarn through the shed, and means for actuating said finger, said actuating means including a guide member slidably receiving said finger and rockable about a

fixed vertical axis, a crank attached directly to said finger and revolvable about a vertical axis, and means on the opposite side of the warp for catching and securing said loops.

5. 3. In a loom, shed-forming means, a filling finger having an eye in one end for the filling yarn, and means for causing said end of the finger to move into and out of the shed in a closed curvilinear path, said means comprising a guide member through which said finger is longitudinally slideable, and means for causing the other end of said finger to move in a circular path.

4. In a loom, shed-forming means, an elongated filling finger having an eye in an end thereof for the filling yarn and supported at one side of the shed, means for moving said finger so that said end thereof moves along the near side of the shed, then into the shed in an arc extending from the near side and open end of the shed to the far side of the shed near the fell of the fabric, then back through the shed near the fell of the fabric to the starting point, and means at the far side of the shed for catching the loop of filling yarn carried through the shed by said finger.

5. In a loom, shed-forming means, an elongated finger having an eye in one end thereof for filling yarn, driving means connected to the other end of said finger, and guide means through which said finger is longitudinally slideable, said driving means including a vertical shaft, a crank arm mounted on said shaft and directly connected to said other end of the finger, and means for rotating said shaft at constant speed.

6. In a loom, shed-forming means, a filling finger having a guide eye in the free end thereof supported at one side of the shed, means for projecting said finger into said shed with a forward sweeping movement in an arcuate path within the shed from the rear to the front of the shed and withdrawing said finger near the fell of the fabric, a beat-up mechanism having elements movable in vertical planes to enter the shed from below at the rear thereof and to move down and out of the shed at the fell of the fabric, said beat-up mechanism being so constructed and arranged as to avoid conflict with the movement of the finger and means for operating said finger and beat-up mechanism so that the finger enters the shed before the beat-up elements leave the shed.

7. In a loom, shed-forming means, a filling finger having a guide eye near its free end for the filling yarn, a pivot for said finger near one end of the fell of the fabric, and means for periodically swinging said finger into said shed about said pivot and withdrawing said finger from said

shed so that its free end follows a path near the fell of the fabric.

8. In a loom, shed-forming means, a filling finger having a guide eye near the free end thereof for projecting loops of filling yarn through the shed, a yarn guide on said loom through which the yarn passes before it reaches the guide eye in the finger, and means for moving said finger outside of the shed relatively to said yarn guide so that sufficient yarn for a loop is drawn through said eye before the finger enters the shed, said moving means thereupon acting to project said eye through the shed rapidly to the further side and to retract said eye relatively slowly to clear the shed.

9. In a loom, shed-forming means, a filling finger having a guide eye near the free end thereof for projecting loops of filling yarn through the shed, a yarn guide on said loom through which the yarn passes before it reaches the guide eye in the finger, means for moving said finger outside of the shed relatively to said yarn guide so that sufficient yarn for a loop is drawn through said eye before the finger enters the shed, said moving means thereupon acting to project said eye through the shed rapidly to the further side and to retract said eye relatively slowly to clear the shed, a second finger and yarn guide on the other side of the shed, and means for operating said second finger with a movement complementary to that of the first-mentioned finger, said movements being timed so that movement of each finger in and out of the shed synchronizes with the movement of the other finger outside of the shed.

10. In a loom, shed-forming means, a filling finger on each side of said shed, each finger having a yarn guide eye in the free end thereof, means for projecting said fingers alternately into said shed so that the guide eye of each finger describes a path entering at the rear end of the shed, extending across the shed and forward to introduce a loop of weft yarn, and returning across the shed near the fell of the fabric, a beat-up mechanism having a plurality of sets of beat-up elements movable into the shed at the rear end thereof, forward within the shed, and out of the shed at the fell of the fabric, and means for causing said fingers and beat-up elements to enter the shed in alternation, said means being constructed and arranged to introduce each finger into the shed while the preceding beat-up element is beating up the previous weft loop and to introduce each beat-up element into the shed before the preceding finger has been withdrawn from the shed.
